UNITED STATES PATENT OFFICE.

RAY C. NEWHOUSE, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

CRUSHER.

Original application filed January 3, 1921, Serial No. 434,493. Divided and this application filed April 13, 1922. Serial No. 552,392.

This invention relates to bearings and is particularly applicable in bearings for gyratory crushers of the type disclosed and broadly claimed in an application of R. C. 5 Newhouse, S. N. 434,493, filed Jan. 3, 1921, of which this application is a division.

In gyratory crushers as hitherto constructed and particularly those in which a comparatively short shaft is desired, that 10 is, in which the distance between the eccentric and the crusher head is not great, there is not much room in the bottom shell. One of the reasons for this is that the diaphragm located in the bottom shell takes up a good 15 deal of a space at at least one side thereof so that if the crusher shaft is to be short the eccentric bearing thereof must be designed so as not to interfere with the diaphragm. In large crushers it is very desirable that 20 the eccentric bearing be artificially cooled. It is one of the objects of this invention to provide a construction whereby this may be accomplished, particularly in crushers of the type set forth.

25 Another object of the invention is the provision of a simple and efficient bearing construction in which a cooling medium may be circulated. Other objects will appear hereinafter as a description of the invention 30 proceeds.

The novel features of this invention will appear from the specification and the accompanying drawings forming a part thereof and showing one embodiment of said invention, and all these novel features are intended to be pointed out in the claims.

35 In the drawings Fig. 1 is a fragmentary vertical section of a gyratory crusher in which the invention has been applied.

40 Fig. 2 is an enlarged horizontal sectional view along the line II-II of Fig. 1, showing the bearing construction.

The crusher shown in Fig. 1 comprises a bottom shell and a top shell 2. The bottom 45 shell is provided with a diaphragm 3 which includes two discharge paths leading to a bifurcated opening in the bottom shell 1, the material leaving the bifurcated opening being discharged onto a chute 19. The foregoing construction is fully set forth and broadly claimed in applicant's copending ease and need not be further described here.

The crusher is provided with a crusher

shaft 4 on which is mounted a crusher head 5. The shaft 4 may be gyrated by an eccentric 6 rigidly associated with a gear 7 which latter is driven by a pinion 8.

The outer bearing surface of the eccentric 6 is surrounded by a sleeve 9 which is mounted and held in a bearing support 10, the parts 9 and 10 forming a bearing member. The bearing support 10 is in turn supported by a plurality of struts one of which, 11, appears in the drawing. The support 10 is preferably formed with a depression 12 facing the outer surface of the sleeve 9. A baffle 13 is provided which divides the space between the sleeve 9 and support 10 formed by the depression 12, into an upper chamber 20 and a lower chamber 21. A 15 plurality of baffles 14 extending in axial planes from the support 10 toward the sleeve 9 are also provided. The baffles 14 stop short of the sleeve 9 so as to leave passages between the ends of these baffles and said sleeve. A baffle 15 similar to baffles 14 but completely bridging the space between support 10 and sleeve 9 is also provided. The baffle 13 is here shown as provided with a hole 16 near the baffle 15. An inlet pipe 17 20 communicates with chamber 20 on the side of baffle 15 opposite to that of hole 16. An outlet pipe 18 communicates with chamber 21 on the same side of the baffle 15. A cooling medium such as water is preferably introduced into pipe 17 and the water then 25 passes around sleeve 9 in chamber 20 in a clockwise direction, being forced near to the sleeve by baffles 14. The water then passes down through hole 16 into chamber 21 in which it flows in a counter clockwise direction and then passes out of pipe 18.

It should be understood that it is not desired to limit the invention to the exact details of construction herein shown and described for various modifications may occur to persons skilled in the art.

It is claimed and desired to secure by Letters Patent:—

1. A crusher comprising a shell, a diaphragm for said shell, a crusher shaft extending through said diaphragm, a crusher head on said shaft on one side of said diaphragm, an eccentric associated with said shaft on the other side of said diaphragm, 100 an outer bearing member for said eccentric 105

- having a portion extending toward said head beyond the general plane of said diaphragm, and means for circulating a cooling medium in said bearing member.
5. 2. A crusher comprising a diaphragm, a crusher shaft, an eccentric associated with said shaft, an outer bearing member for said eccentric, having a portion above the general plane of said diaphragm, said member including a substantially cylindrical sleeve surrounding said eccentric, and a member, provided with an internal depression, fitted over said sleeve whereby a passage is provided for the circulation of a cooling medium 10 in said bearing member.
15. 3. A crusher comprising a bottom shell, a crusher shaft, an eccentric associated with said shaft, an outer bearing for said eccentric, a support member for said bearing associated with said shell, whereby the thrust from said eccentric is transmitted to said shell, said support member having an annular recess surrounding said bearing, and a baffle forming part of said support member 20 and dividing said recess into an upper and lower chamber.
25. 4. A crusher comprising a crusher shaft, an eccentric associated with said shaft, an outer bearing member for said eccentric, said member including a substantially cylindrical sleeve surrounding said eccentric, a support member provided with an internal depression, over said sleeve, a baffle having an opening, said baffle dividing said depression into 30 an upper and lower chamber whereby two 35 passages around said sleeve are provided for the circulation of a cooling medium.
40. 5. A crusher comprising a crusher shaft, an eccentric associated with said shaft, an outer bearing member for said eccentric,
- said member including a substantially cylindrical sleeve surrounding said eccentric, a support member provided with an internal depression, over said sleeve, a baffle having an opening, said baffle dividing said depression into an upper and lower chamber and a plurality of baffles extending in axial planes from said support member toward said sleeve, one of said baffles completely bridging the space between said support member and said sleeve. 45
6. 6. A crusher comprising a crusher shaft, an eccentric associated with said shaft an outer bearing member for said eccentric, said member including a substantially cylindrical sleeve surrounding said eccentric, a support member provided with an internal depression, over said sleeve, a baffle having an opening, said baffle dividing said depression into 50 an upper and lower chamber, a plurality of baffles extending in axial planes from said support member toward said sleeve, one of said baffles completely bridging the space between said support member and said sleeve, an inlet and outlet pipe connected respectively to said chambers near one side of said last named baffle. 55
7. 7. A crusher comprising a bottom shell of the type having a diaphragm providing two discharge paths leading respectively to two 60 adjacent discharge openings in said shell, a crusher shaft, an eccentric associated with said shaft, an outer bearing for said eccentric, and a water jacket for said bearing disposed within the confines of said bottom 65 shell. 70

In testimony whereof, the signature of the inventor is affixed hereto.

RAY C. NEWHOUSE.
